CALIPER FOR DETERMINING THE SHAPE AND DIAMETER OF WELL BORES

Mordica O. Johnston, Glendale, and Jack A. Moosman, Los Angeles, Calif., assignors, by mesne assignments, to Johnston Testers, Inc., Houston, Tex., a corporation of Delaware

Application August 10, 1951, Serial No. 241,262

4 Claims. (Cl. 33—178)

1

This invention relates to an oil well tool and particularly to a caliper for determining the shape and diameter of well bores.

A main object of the present invention is to provide a well caliper having a plurality of outwardly urged caliper arms adapted to be restrained against outward movement by impact responsive means which are responsive to an impact to release the arms for outward movement into engagement with the walls of a well bore.

Another object of the present invention is to provide a well caliper having a plurality of outwardly movable swingably mounted caliper arms each of which is adapted to separately and independently actuate a stylus mounted on a key member which is guided for longitudinal movement, the styluses being arranged to make separate records on a suitable chart.

A further object of the present invention is to provide a well caliper as described in the immediately above paragraph in which there are impact responsive means for releasably holding the arms in their inward positions responsive to an impact to release the arms for outward movement.

Various other objects will be apparent from the following description taken in connection with the accompanying drawings in which:

Fig. 1 shows a vertical mid-section through a well caliper embodying the concepts of the present invention and shown with the caliper arms thereof in retracted positions.

Fig. 2 is a horizontal section through the caliper disclosed in Fig. 1 taken along line 2—2 of Fig. 1.

Fig. 3 is a horizontal section through the caliper disclosed in Fig. 1 taken along line 3—3 of Fig. 1.

Fig. 4 is a view similar to Fig. 1 but showing the caliper arms as having been released and being in engagement with the walls of a well bore.

Referring to the accompanying drawings, wherein similar reference characters designate similar parts throughout, the well caliper comprises a body generally entitled 9 made up of a plurality of parts including a tubular chart housing 11, an upper plug 13 and a lower plug 15, all suitably threaded together as shown. There is a wire line socket 17 threaded into plug 13 and locked in place by a check nut 19. Body 9 is adapted to be supported by a wire line 21 having the lower end thereof suitably connected to the wire line socket 17 in the usual fashion.

Formed on lower plug 15 is a depending skirt 23 having a plurality of circumferentially equally spaced notches 25 therearound to receive a plu-

2

rality of bell crank shaped caliper arms 27 which are swingably mounted for radial movement about pivot pins 29 receivable in depending segments 28 formed by notches 25. The lower ends of arms 27, as the parts are depicted in Fig. 1, are rounded at 31 for proper engagement with the walls A, shown in Fig. 4, defining the well bore.

Supported from lower plug 15 by hanger bolts 33 is a bullnose or guard member 35 provided for the purpose of protecting the caliper arms during descent into a well bore. The guard member 35 has a flange 37 formed thereon spaced upwardly from the lower nose portion and circumferentially slotted at equally spaced points thereabout to receive the lower ends of caliper arms 27. Hanger bolts 33 have the lower ends thereof reduced and threaded to receive nuts 39, the upper ends of the hanger bolts being threaded into depending segments 28 on plug 15. The reduction of the lower ends of hanger bolts 33 provide shoulders for bearing against the flange 37 to space the guard 35 at the proper distance from the plug 15.

Caliper arms 27 are spring-urged outwardly by tension springs 41 hooked at their lower ends through apertures 43 in flange 37 onto the underside of flange 37 and connected at their upper ends to links 45 swingably mounted on pivot pins 47 provided on the upper ends of caliper arms 27. The upper crank ends of caliper arms 27 are connected in a manner to be described to the chart mechanism for making separate records.

The outwardly urged caliper arms 27 are restrained against outward movement by a sleeve 51 telescopically received over body 9 and urged upwardly by a compression spring 53 disposed in engagement with check nut 19 at one end and a cap 55 at its other end, said cap being threaded into sleeve 51 as shown in Fig. 1. Spring 53, therefore, urges sleeve 51 into a position to uncover the surrounded caliper arms 27 and to release the arms for outward radial movement into engagement with the walls A defining the well bore. However, the sleeve 51 is releasably locked against upward movement by a pair of shear pins 57 connecting cap 55 and wire line socket 17. Suitable set screws 59 are provided for retaining the shear pins in place and allowing replacement of the pins after operation of the well caliper.

Sleeve 51 is adapted to be released for upward movement, under the influence of spring 53, by a go-devil 61 which is received over wire line 21

and dropped down the well into engagement with cap 55, the impact serving to shear pins 51 to allow the upward releasing movement of sleeve 51. Upon upward movement of sleeve 51, the caliper arms move outwardly from the position shown in Fig. 1 to the position shown in Fig. 4 into engagement with the walls A of the well bore and each caliper arm is moved inwardly or outwardly, in accordance with the contour of the surface which it encounters, independently and separately from the other caliper arms, thereby indicating the different diameters of the well bore.

As previously mentioned, the upper ends of caliper arms 27 are operatively connected to a chart mechanism for making separate records. This arrangement is as follows: The upper ends of caliper arms 27 are connected by links 65, which preferably form extensions of links 45, to crossheads 67 slidably received within bore 69 provided in plug 15, said crossheads having pistons 71 slidably extending through the plug 15. There is suitable packing 73 disposed around pistons 71 and held in place by packing glands 75.

Within tubular chart housing 11, is disposed a cylindrical chart support 81 adapted to be constantly driven when the caliper is put in operation by a clock mechanism 83. Disposed about the chart support 81 and slidably fitting within and secured to housing 11 is a sleeve 85 having the interior surface thereof disposed in spaced relation to the exterior surface of the cylindrical chart support 81 so as not to interfere with the rotation of the chart support. Sleeve 85 has provided on the exterior thereof a plurality of longitudinal circumferentially spaced keyways 89 for the reception of the shanks 91 of a plurality of key members 93 spring-urged downwardly by compression springs 95 contained between the upper ends of shanks 91 and the shoulders 97 formed on sleeve 85 at the upper terminals of keyways 89. The body portions of the key members are slidably received within downwardly opening clearance slots formed in the lower end of sleeve 85 in registry with the keyways.

Each key member 93 has a stylus 99 secured thereto and disposed in a position to engage a chart supported on the interior of cylindrical chart support 81.

Compression springs 95 urge the key members 93 downwardly into engagement with the upper ends of pistons 71. Therefore, any movement, up or down, of pistons 71 will serve to effect an equal movement of the particular stylus carried by the key member engaging the movable pistons.

As clearly shown in Fig. 1, the individual styli are staggered with relation to one another so that the records produced thereby do not overlap.

The operation of the device is as follows: When it is desired to caliper a well bore, the caliper may be lowered into the well to the location which is desired to be calipered and a go-devil 61 is dropped down the wire line to strike the cap 55 and release the sleeve 51 for upward movement under the influence of compression spring 53. Such upward movement releases the caliper arms 27 for outward radial movement under the influence of tension springs 41. Outward movement of caliper arms 27 results in an accompanying downward movement of pistons 71 and a following movement of key members 93 carrying styli 99 along the interior of cylindrical chart support 81. The outward movement of caliper arms 27 will be limited by their contact

with the walls defining the well bore and eventually by the engagement of the caliper arms 27 with the walls which define the oblique upper ends of notches 25 in plug 15. The caliper is then drawn upwardly through the well bore, each caliper arm moving inwardly or outwardly in accordance with the contour of the surface which it engages, therefore making a plurality of separate individual recordings on the chart carried by the cylindrical chart support 81.

It may also be desirable to caliper the well all the way in and all the way out instead of merely lowering the caliper into the well and then withdrawing the caliper. However, the normal use will be to lower the caliper into the well and to release the caliper arms by dropping a go-devil down the wire line to effect the release of the caliper arms as previously described.

While we have shown the preferred form of our invention, it is to be understood that various changes may be made in its construction by those skilled in the art without departing from the spirit of the invention as defined in the appended claims.

Having thus described our invention, what we claim and desire to secure by Letters Patent is:

1. A well caliper, comprising a caliper body adapted to be lowered into a well on the lower end of a wire line, a plurality of outwardly urged caliper arms swingably mounted on the caliper body for movement from inward inoperative positions to outward operative positions, a sleeve movably carried by the body and surrounding the upper ends of the arms to retain them in their inward positions, and means located at the top of said body in the vicinity of the wire line for releasably connecting the sleeve to the body in its arm retaining position, said means being responsive to the impact of a go-devil dropped down the wire line to release the sleeve and permit arm releasing movement, and means normally biasing said sleeve toward its arm releasing position whereby the arms can be released at any place along the well bore by positioning the body at such place and dropping a go-devil down the wire line.

2. A well caliper, comprising a caliper body adapted to be lowered into a well on the lower end of a wire line, a plurality of outwardly urged caliper arms swingably mounted on the caliper body for movement from inward inoperative positions to outward operative positions, a sleeve movably carried by the body and surrounding the upper end of the arms to retain them in their inward positions, spring means urging the sleeve in a direction to release the arms, and means located at the top of said body in the vicinity of the wire line for releasably connecting the sleeve to the body in its arm retaining position, said means being responsive to the impact of a go-devil dropped down the line to release the sleeve, whereby the arms can be released at any place along the well bore by positioning the body at such place and dropping a go-devil down the wire line.

3. A well caliper, comprising a caliper body adapted to be lowered into a well on the lower end of a wire line, a plurality of outwardly urged caliper arms swingably mounted on the caliper body for movement from inward inoperative positions to outward operative positions, a sleeve movably carried by the body and surrounding the arms to retain them in their inward positions, a cap at the top of the body secured to the sleeve and through which the wire line extends,

means normally biasing the sleeve toward its arm releasing position, means for holding the sleeve in its arm retaining position responsive to the impact of a go-devil with the cap to release the sleeve for arm releasing movement, whereby the arms can be released at any place along the well bore by positioning the body at such place and dropping a go-devil down the wire line.

4. A well caliper, comprising a caliper body adapted to be lowered into a well on the lower end of a wire line, a plurality of outwardly urged caliper arms swingably mounted on the caliper body for movement from inward inoperative positions to outward operative positions, a sleeve movably carried by the body and surrounding the arms to retain them in their inward positions, a cap at the top of the body secured to the sleeve and through which the wire line extends, spring means urging the sleeve in a di-

rection to release the arms, and means for holding the sleeve in its arm retaining position, responsive to the impact of a go-devil with said cap to release the sleeve for arm releasing movement.
